UNITED STATES PATENT OFFICE

172,757

ICE CRUSHER CASING

Walter E. Moore, Bel Nor, Mo., assignor to Swing-A-Way Manufacturing Company, St. Louis, Mo., a corporation of Missouri

Application February 8, 1954, Serial No. 28,888

Term of patent 14 years

(Cl. D89—1)

To all whom it may concern:

Be it known that the undersigned, Walter E. Moore, a citizen of the United States, residing at Bel Nor 21, Missouri, has invented a new, original, and ornamental Design for an Ice Crusher Casing, of which the following is a specification, reference being had to the accompanying drawing, forming a part thereof, in which:

Fig. 1 is a top plan view of an ice crusher casing showing my new design;

Fig. 2 is a front elevational view thereof;

Fig. 3 is a side elevational view thereof; and

Fig. 4 is a rear elevational view thereof.
The undisclosed side of my ice crusher casing is identical with the side disclosed in Fig. 3.

I claim:

The ornamental design for an ice crusher casing, as shown.
